GARDEN AND BEACH UMBRELLA

Ray A. Russell, Santa Ana, Calif.

Application August 17, 1946, Serial No. 691,269

8 Claims. (Cl. 135—46)

1

This invention relates particularly to structures for large umbrellas of the type to be set up in stationary positions, at least temporarily, and commonly known as garden umbrellas and beach umbrellas. These frequently have means for tilting the umbrella canopy with respect to a center post or staff which carries the canopy and is adapted for being thrust into the earth or sand or otherwise held upright.

The principal objects of the invention are to provide novel, efficient and simple structures for use in umbrella manufacture of the indicated type and to furnish to the purchasing public devices which are highly serviceable while at the same time relatively economical.

A more specific object is to provide a novel, easily operable, and unusually durable tilting head or joint whereby the opened canopy may be locked against swinging movement both up and down from a tilted position, as well as to provide novel, serviceable and simple means for joining and latching two separable portions of the post.

A further object is to provide novel, simple and serviceable means for latching the opened canopy in open position. Another object is to provide novel, simple and serviceable means for securing the center of the canopy permanently to the top of the post, and for slidably mounting the lower ends of the usual canopy bracing ribs upon the post.

Further objects, and features of novelty, will become apparent upon reference to the accompanying drawing wherein one useful embodiment of the invention is disclosed by way of example.

In the drawing:

Fig. 1 is a fragmentary elevational view of the assembled parts of the umbrella, and showing the canopy-positioning parts in normal canopy-elevating position, portions being broken away to facilitate disclosure;

Fig. 2 is a similar view on an enlarged scale of the tilting joint or head indicated at the middle of Fig. 1;

Fig. 3 is a horizontal cross section taken on the line 3—3 of Fig. 1;

Fig. 4 is an enlarged elevational view of the canopy securing means shown at the top of Fig. 1, portions being broken away;

Fig. 5 is a horizontal cross section taken on the lines 5—5 of Figs. 1 and 4; and

Fig. 6 is a vertical sectional view on an enlarged scale of the latching means joining two post sections as indicated by the line 6—6 of Fig. 1.

2
The structure illustrated includes an aluminum or other metal post 10 comprising a lower tube section 11, an upper tube section 12, an intermediate tube section 14, and a tilting joint 15 joining the tube sections 12 and 14. A plunger lock 16 connects the tube section 11 to the tube section 14. On the top of the upper tube section 12 of the post 10 a rib and canopy retainer 18 is mounted whereby to position the inner and upper ends of the usual canopy supporting ribs 19. Below the retainer 18, a spreader ring structure 20 is slidably mounted on the post 10 for the purpose of positioning the usual bracing and spreading ribs 21. The ring structure 20 is held in operative position by a supporting latch 22. The tilting joint 15 comprises an upstanding shank 25 integral with a lower plug 26 (Fig. 2) which fits into the upper end of the lower tube section 11, the plug 26 being positioned by an overhanging flange 27 and locked in place by a lock pin 28 secured in a socket 29 in the plug 26 and in a corresponding aligned hole in the tube section 11. The lower portion of the shank 25 carries a transverse pivot pin 30 whose ends project and receive the lower ends of a pair of spaced arms 32 which are integral with an upper plug 33 fitted into the lower end of the upper tube section 12 and having a flange 34 seated against the lower edge thereof. A lock pin 35 fixed in a hole in the tube section 12 and in a socket 36 in the plug 33 insures proper positioning of the respective parts.

As will be seen from Figs. 2 and 3, the upstanding shank 25 is generally quadrilateral in cross section and is narrow enough in one transverse direction to accommodate at its sides the arms 32 within the diametrical limits of the post sections 11, 12, and 14. Also, the shank 25 is only about half that diameter in the other transverse direction so that it provides an inner vertical face 37 against which stop means in the form of a latch pin 38 in the arms 32 and a pivoted latch bar 40 may lie, as in Fig. 1. An inner vertical pocket is also thus provided between the arms 32 to receive the latch bar 40; see also Fig. 3. In such folded or collapsed position, the parts are aligned. The latch pin 38 is secured in the upper portions of the arms 32 and spans the space between them, this pin 38 being disposed sufficiently to one side of the median line of the arms 32 to permit the folding of the parts.

The latch bar 40 moves between the arms 32 and above the latch pin 38, and is provided on its under edge with spaced notches 41 adapted selectively to receive the latch pin 38 for as many

positions of adjustment of the arms 32 as the notches 41 will accommodate. The upper end of the latch bar 40 carries an offset integral lug 40a which is received between two upstanding integral ears 25a on the upper or outer end of the shank 25 and upon a pivot 42 carried by the ears 25a. By reason of such mounting the latch bar 40 and the arms 32 may be swung between any tilted position of adjustment, such as seen in Fig. 2, and the aligned position of Figs. 1 and 3. As best indicated in Fig. 3, the heads of the pivot pin 30 and the latch pin 38 are received in countersunk seats in the sides of the arms 32.

As will be apparent from the above description, the latch bar 40 may be swung out from its collapsed position of Fig. 1 into an angular position such as that of Fig. 2. To facilitate such swinging movement, the lower end of the latch bar 40 is provided with finger depressions 43 on opposite sides and the corresponding lower corners of the arms 32 are cut away at 44 to provide for access to such depressions. When the arms 32 and the upper tube section 12 have been disposed at an angle to tip the canopy as desired, the latch bar 40 is depressed to dispose the walls of the adjacent notch 41 about the latch pin 38. These walls of the notches 41, as indicated in Fig. 2, prevent accidental further movement of the arms 32 both upward and downward, it being necessary to lift the latch bar 40 to accomplish a different adjustment.

It is to be noted that an uppermost notch 45 is formed in the latch bar 40 for the purpose of receiving the latch pin 38 when in collapsed position. In view of the short radius, the wall 45a of the notch 45, most remote from the pivot 42, is appropriately curved approximately as shown to provide for the necessary movement of the bar 40. This curved wall 45a performs another function, in that, if the latch bar 40 is lifted a short distance but not enough to clear the notch 45, swinging of the arms 32 will cause the latch pin 38 to work upon the wall 45a as a cam face and thereby lift the latch bar 40 until the notch 45 is cleared. In this instance the next notch 41 will not be cleared and the latch pin 38 will engage therein, thereby preventing further tilting movement unless the latch bar 40 is lift manually. Similarly, if in collapsing the joint 15, the arms 32 have been moved a little short of alignment, depression of the latch bar 40 will cause the curved wall 45a again to act as a cam and force the latch pin 38, and hence the arms 32, into aligned position wherein the latch pin 38 and hence the arms 32 are held by the latch bar 40.

To insure retention of the latch bar 40 in aligned position, a detent 46 may be used which is urged into a recess 47 in the lug 40a by means of a spring 48 which is received in a pocket 49 in the upper portion of the shank 25 and is disposed about a stem 46a integral with the detent 46, which detent constitutes a head on the stem and provides thereby a bearing surface for the top of the spring 48.

Thus, the latch bar 40 serves to lock the arms 32 in collapsed position and aligned with the intermediate tube section 14. When in the above described aligned position, the parts of the tilting joint 15 assume the circular cross sectional relationship shown in Fig. 3, and this position permits the spreader ring structure 20 to slide up and down thereover for raising and lowering the canopy. When in elevated position, the ring structure 20 is retained by the elongated spring-controlled supporting catch 22 whose upper end

portion projects partially through a slot 50 in the upper tube section 12 and whose upper end wall 51 normally acts as a stop, the intermediate portion of the catch 22 bearing upon the lower edge of the slot 50 as a movement-limiting means. The lower end of the supporting catch 22 as shown is integrally provided with a positioning lug 52 which projects somewhat loosely through a corresponding hole in the adjacent side wall of the tube section 12. The catch 22 is controlled by an elongated wire spring 54, one end of which is embedded in the lower end of the catch 22 adjacent the lug 52 and the other end of which is curved downward and bears against the inner wall of the tube section 12 on the side opposite from the lug 52. Thus, the top end wall 51 normally retains the spreader ring structure 20 and its canopy in elevated position, the upper end portion of the catch 22 being retractable, as by pressure of the thumb or finger, against the action of the spring 54 to permit the ring structure 20 to be lowered.

The spreader ring structure 20 and the retainer 18 for the canopy ribs 19 are substantially the same in construction, one being inverted with respect to the other, and each being formed of two notched, telescoped ring members enclosing a split spring ring. The spreader ring structure 20 comprises an inner somewhat elongated, sleeve-like retaining ring 60a and an outer retaining ring 62a fitting upon the ring 60a both being provided with notches 63a in their upper edges and receiving between them a split spring wire lock ring 64a which passes through eyes 21a commonly provided on the umbrella bracing ribs 21. This construction is shown in greater detail in conjunction with the retainer 18 for the canopy ribs 19.

The retainer 18 comprises, as best seen in Figs. 4 and 5, an inner retaining ring 60, an outer retaining ring 62, both of these rings having notches 63 in their lower edges, and a split spring wire lock ring 64. These parts correspond with the parts similarly numbered, in conjunction with the suffix *a*, of the ring structure 20. In both instances, the outer rings 62, 62a, are provided with short grooves in the resultant fingers between the notches 63, 63a. Such grooves, as indicated at 65, are deep enough to accommodate the entire thickness of the wire lock rings 64, 64a when the latter are expanded and opposing shallow locking grooves in the inner retaining rings 60, 60a, as indicated at 66, Fig. 5, accommodate approximately one-half the cross-sectional thickness of the wire rings when the latter are released and permitted to contract into locked position. The spring lock ring 64 receives eyes 19a on the canopy ribs 19, and the spring lock ring 64a receives the corresponding eyes 21a on the bracing ribs 21, these eyes being disposed in the notches 63, 63a when the parts are assembled and being locked in position when the spring lock rings contract. As best seen in Fig. 5, each spring lock ring may be provided at one end with an offset 68 received in a hole 69 in the outer retaining ring 62, 62a to facilitate assembly or removal of the parts.

As will be apparent, when the spring lock rings 64, 64a are expanded into the grooves 65, the inner retaining ring 60, 60a may be telescoped within the outer retaining rings 62, 62a, the respective notches 63 being aligned to receive the eyes 19a, 21a of the ribs 19, 21. The spring lock rings having been released, they expand into the shallow locking grooves 66 when the retaining rings have attained their relative operative telescoped positions. In such assembled condition the inner

sleeve-like ring 60a of the spreader structure 20 is free to slide on the post 10 and carry with it the bracing ribs 21.

The assembled canopy retainer 18 is installed upon the top of the upper tube section 12 of the post 10, its position being determined, if desired, by a flange 70 on the inner ring 60. Retention is accomplished by means of a plurality of anchoring pins 72 which project through corresponding holes in the retaining rings 60, 62 and in the tube section 12 and into the base of a wooden plug 75 tightly fitted into the top of the tube section 12 and having an exposed finished extremity which may be tapered as shown or decorated as required. The pins 72 are located at any appropriate positions above or below the lock ring 64 whereby to avoid the latter.

For the purpose of attaching and detaching the lowermost tube section 11 of the post 10, whereby to make the entire umbrella collapsible into a unit of minimum length, and yet have a staff adequately long for use, the plunger lock 16 is employed in conjunction with a telescopic connection between the tube sections 11 and the intermediate tube section 14. In the form shown, a sleeve 80 (Fig. 6) is fixed in the upper end of the tube section 11 and is adapted to be removably telescoped into the tube section 14. The plunger lock 16 is carried by the sleeve 80, and comprises a relatively elongated internal plunger portion 82 disposed radially of the sleeve 80. A short normally exposed plunger portion 83 of smaller diameter than the elongated portion 82 connects the portion 82 with a manipulating head 84. The lower end of the tube section 14 is provided with a keyhole type of slot 85 whose lower end is open and whose lower portion is wide enough to pass the short section 83 but too narrow to pass the larger diameter portion 82. However, the upper end of the slot 85 is large enough to receive the outer end of the larger diameter portion 82 whereby, when the plunger is extended the tube sections 11 and 14 are locked together but when depressed the smaller diameter portion 83 may pass through the narrow portion of the slot for separation of the mentioned tube sections 11 and 14. The plunger is mounted by positioning the outer end of its larger diameter portion 82 in a hole 86 in the sleeve 80 and its inner end in a small sleeve 88 containing an extending spring 90. A cross pin 92 in the plunger portion 82 between the hole 86 and the inner end of the sleeve 88 both limits the outward movement of the plunger to locking position and its inward movement to releasing position wherein the cross pin 82 strikes the sleeve 88. The outer end of the sleeve 88 is fixed in the adjacent wall portion of the sleeve 80 and carries a positioning pin 94 which provides a seat for the spring 90 and may be used also in connection with positioning of the sleeve 88.

In operation of the plunger lock 16, the head 84 is depressed to bring the reduced diameter portions 83 into alignment with the narrow portion of the slot 85, whereby to admit the sleeve 80 into the intermediate tube section 14, as in Fig. 6. Release of the head 84 permits the spring 90 to extend the plunger so that the outer end of the larger diameter section 82 becomes locked in the enlarged upper end of the slot 85. The post 10 thus assembled may then be thrust into the earth, for example, the spreading ring structure 20 moved upward above the supporting catch 22 to elevate and hold the canopy, and the tilting joint 15 actuated to any desired angle, as above described.

Since various modifications of the generic structure disclosed may be made within the scope of the claims, it is intended that these also shall be covered hereby.

5 I claim as my invention:

1. In combination in an umbrella structure: a post having two sections; and a tilting joint disposed between said two sections, said joint comprising a shank secured to and projecting from one of said sections, an arm secured to and projecting from the other of said sections and pivotally attached to said shank to align therewith in extended position, a latch bar pivotally connected to the outer end of said shank and adapted to fold alongside of said shank into collapsed position, and stop means carried by said arm, said arm providing a transverse passage adjacent said stop means and receiving said latch bar, said latch bar having locking means to engage said stop means and prevent swinging movement between said shank and arm in either direction, both said stop means and the pivotal mounting of said latch bar on said shank being spaced substantial distances from the point of pivotal connection between said shank and said arm, said shank and arm being collapsible into aligned position and said bar being collapsible into a pocket in said joint formed by said passage and to lie alongside said arm and said shank and to engage and retain said stop means in locked position closely adjacent said outer end of said shank.

2. In combination in a tilting joint for umbrellas: a shank member adapted to be secured to one section of an umbrella post to project therefrom; an arm member adapted to be secured to a second section of said umbrella post and project therefrom; pivot means pivotally connecting said shank member and arm member for movement between an aligned position and positions of angular adjustment with respect to each other; a latch bar pivoted upon one of said members; and stop means carried by the other of said members, said latch bar having cooperating means for engagement with said stop means to retain said members in adjusted position, said stop means being spaced longitudinally along its member from said pivot means, and a transverse passage being provided by said arm member through which said latch bar slidably extends, said stop means being movable to a position adjacent the pivotal mounting of the latch bar on said one of said members when the two members are aligned and said latch bar being movable to a position where it engages about said stop means when said members are aligned whereby to lock said members in aligned position.

3. In combination in a joint for an umbrella: two joint members adapted respectively to be attached to and project from opposing sections of an umbrella post and be interposed between said sections; pivot means pivotally connecting said members together for movement between aligned position and positions of angular adjustment with respect to each other; a latch bar pivoted upon one of said members; and cooperating stop means on the other of said members for latching engagement with said bar and retention of said members in adjusted position, said stop means being spaced longitudinally along its member from said pivot means, a transverse passage being provided by said other member adjacent said stop means, said bar lying in said passage, said bar having means for adjustably engaging said stop means in locking relationship, said stop means being movable against said one of said

members when said members are aligned, and said latch bar being movable about its pivot into collapsed relationship alongside said members when said members are in aligned position and engaging said stop means to maintain said members aligned.

4. A combination as in claim 3 wherein end portions of said two members overlap each other, said latch bar being pivotally mounted upon the outer end of one of the members.

5. A combination as in claim 3 wherein said locking means on said latch bar includes notches formed in said bar and having side walls, said side walls engaging said stop means to prevent movement in opposite directions.

6. A combination as in claim 3 including detent means carried by the member upon which said latch bar is pivoted for locking said latch bar in collapsed position alongside such member upon which said bar is pivoted.

7. In combination in an umbrella structure: a post having two sections; and a tilting joint between said two sections, said joint comprising a shank secured to and projecting from one of said sections, an arm secured to the other of said sections and pivotally attached to said shank at the base thereof remote from its outer end, and a latch bar having connections at spaced points with said arm and with the outer end of said shank and adapted to fold alongside thereof to collapsed position, said connections including a pivot mounting between said latch bar and one of said arm and said shank for swinging of said bar, and said connections including cooperating means on said bar and the other of said arm and shank to lock said arm and shank together against swinging movement in either direction when tipped at an angle relative to one another, said cooperating means including stop means

carried by said arm and notches carried by said bar for selective engagement with said stop means, said arm and shank providing a pocket into which said bar folds, said notches being directed toward said shank and disposed against said stop means when said latch bar is folded into collapsed position in said pocket.

8. A combination as in claim 7 wherein said pivot mounting is located on said outer end of said shank and said stop means is a latch pin on said arm and said notches are located on the underside of said latch bar and have side walls for engaging said latch pin and preventing movement of said bar on said pin in either longitudinal direction.
